RAIL CONNECTING DEVICE

Angelo Lorio, Brooklyn, N. Y.

Application August 29, 1950, Serial No. 182,092

2 Claims. (Cl. 238—223)

1

My invention relates to new and useful improvements in a rail construction and is directed more particularly to the provision of a rail connecting structure which provides a flush joint at the abutting ends of the rails whereby not only pounding of train wheels passing over the joint but also resulting damage to both wheels and rail are eliminated.

It is the principal object of my invention to provide a novel and improved construction of the type wherein is provided a splicing means adapted to be fitted into the ball or head of a rail at the abutting ends and there is the provision of means to permit expansion and contraction of the rails.

One of the primary purposes of my invention is to provide structural and operational improvements in devices of the class to which reference has been made, which improvements provide important, distinct advantages in strength, durability, and the like.

It is another object of my invention to provide a reversible connecting member for connecting adjacent rail ends together and for forming an effective tread surface at the joint between the ends and for positively preventing the sagging of the rail ends under the weight of the rolling stock.

It is a still further object to provide a construction which will hold the meeting ends of two track rails in more perfect alignment than has heretofore been possible, which will prevent them from spreading laterally, shifting longitudinally, and raising vertically.

With the above primary object in view, it is another object of my invention to provide a construction of the above described character in which the number of operating parts is greatly reduced and which is compact in accordance with the demands and desires of rail manufacturers and railroad operators alike, and which is not only distinctive in its appearance and practical in its value but also reliable in its operation and efficient in its use.

It is a still further object to provide a device which is constructed of parts which are adapted to be readily assembled and which when once assembled are positively and securely retained in operative relationship and which cannot be accidentally separated from each other.

Other prime objects of my invention include: first, the securing of a higher degree of accuracy in the manner of work performed therewith than has heretofore been possible with prior devices known in the art; second, the attainment of a greater ease in adjustment and repairs due to its simplification in design and its unique composition of parts; third, the provision of a construction which may be readily installed with respect to the various purposes for which it is

2

intended; and fourth, the provision of such other improvements in and relating to rail construction of the type above referred to as are hereinafter described and claimed.

5 My invention also consists in certain new and original features of construction and combination of parts hereinafter set forth and claimed in conjunction with the annexed drawings which illustrate a certain form of embodiment thereof, which form is deemed preferable and is a specific disclosure for the purpose of illustrating an embodiment of the invention by way of an example since the same has been found in practice to give satisfactory and reliable results, although it is to be understood that the various parts of 10 which the invention consists, can be variously changed within the scope of the appended claims without departing from the broad aspects and spirit of the invention.

All of the above cited objects I accomplish by means of such structure and relative arrangement of parts thereof as will fully appear by a perusal of the description below and by various specific features which will be hereinafter set forth. To these above and other ends and with the foregoing and various other features and advantages and objects of my invention as will become readily apparent as the description proceeds, my invention consists in certain novel features of construction and in the combination and arrangement of parts as will be hereinafter more particularly pointed out in the claims hereunto annexed and more fully described and referred to in connection with the accompanying drawings wherein:

Fig. 1 is a perspective view of the end of a rail of my invention;

Fig. 2 is a perspective view of the connector of my invention;

Fig. 3 is a top plan view of the ends of two adjacent rails in combination with the connector of my invention; and

Fig. 4 is a side elevational view of the device shown in Fig. 3.

In the following description and claims, various 45 details will be identified by specific names for convenience. These names, however, are intended to be as generic in their application as the art will permit.

Referring now to the drawing more in detail, in which similar characters of reference indicate corresponding parts in the several figures, and referring more particularly to the preferred form of my invention selected for illustrative purposes, I have shown a rail end of a rail at 2 in Fig. 1.

50 The rail ends of the rails connected in accordance with the invention are similar so that one only need be described in detail.

The rail 2 has an upper ball or head 4 and a lower flange 6 which are connected by a vertical

web 8 of less transverse width or thickness than the transverse width of said head.

A recess 12 is provided which extends inwardly from the end of the rail end and downwardly from the upper side of the rail head. The rail end is provided with a body portion 16 which may have outer sides which are flush with the sides of the rail head.

The recess has parallel vertical sides 14 at the end of rail extending to a point intermediate the ends of the recess and relatively converging sides 18 extending said point to the inner end thereof forming a V.

Upper end portions of the body portion and rail head at the inner end of the rail end are disposed downwardly providing shelves 20 and shoulders 22 at opposite sides of the recess, as shown.

Holes 37 are provided through the body portion of the rail end for bolts.

The recess terminates in a bottom 16 disposed upwardly from the lower face of the flange 6.

An elongated connector 30 has an intermediate portion and opposite end portions 33.

Opposite sides of the intermediate portion of the connector are disposed vertically and parallel to fit the sides 14 of the recesses of the rail ends.

Opposite sides of the end portions of the connector are vertically disposed and in parallel for fitting the sides 18 of the recesses.

Ledges 36 extend outwardly from opposite sides of the intermediate portion of the connector and have lower seats for resting on the shelves 20 of the rail ends between the shoulders 22.

The connector is provided with bolt holes 39 for registering with the holes 37 of the rail ends.

In connecting the rail ends the connector is inserted in the recesses thereof so that the ledges rest upon the shelves 20 and fills in the spaces between the shoulders 22.

Bolts 40 extend through the holes 37 and 39 of the rail ends and connector which with nuts 42 and washers secure the parts together.

Preferably the overall length of the connector is slightly less than the length of the combined recesses and the ends of the ledges 36 are out of contact with the shoulders 22 to allow for contraction and expansion in the rails connected according to the invention.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Connecting construction for adjacent ends of railroad rails having upper and lower horizontally disposed heads and flanges and vertically disposed webs therebetween comprising in combination, the ends of said rail ends provided with body portions of relatively greater transverse thickness than the transverse thickness of said webs and having outer vertical side faces disposed in substantial parallelism with the longitudinal side faces of the heads of said rails and extend-

ing between the heads and flanges thereof, said heads and body portions provided with recesses having open upper sides and outer ends extending inwardly longitudinally from the ends of the rails and having horizontally disposed bottoms spaced upwardly from lower faces of said flange, said recesses having opposite vertically disposed sides with the said sides being in parallelism from outer ends of the rails to a point intermediate the ends of the recesses and then relatively converging to inner ends of said recesses, an elongated connector having opposite vertically disposed sides, intermediate portions and end portions of the sides of said connector being complementary to the sides of the recesses and said connector being insertable downwardly into recesses of the rail ends in aligned abutting relation thereof and having a lower face resting on the bottoms of said recesses, said rail ends and connector provided with aligned openings, and bolts extending through said openings.

2. Connecting construction for closely adjacent ends of railroad rails having upper and lower horizontally disposed heads and flanges and vertically disposed webs therebetween comprising in combination, the ends of said rail ends provided with body portions of relatively greater transverse thickness than the transverse thickness of said webs and having outer vertical side faces disposed in substantial parallelism with the longitudinal side faces of the heads of said rails and extending between the heads and flanges thereof, said heads and body portions provided with recesses having open upper sides and outer ends extending inwardly longitudinally from the ends of the rails and having horizontally disposed flat bottoms spaced upwardly from lower faces of said flange, said recesses having opposite vertically disposed sides with the said sides being in parallelism from outer adjacent ends of the rails to a point intermediate the ends of the recesses and then relatively converging to inner ends of said recesses, an elongated connector having opposite vertically disposed sides, intermediate portions and end portions of the sides of said connector being complementary throughout their length to the sides of the recesses and said connector being insertable downwardly into recesses of the rail ends in aligned closely adjacent relation thereof and having a continuous flat lower face resting throughout the length thereof on the bottoms of said recesses, said rail ends and connector provided with aligned openings, and bolts extending through said openings, upper portions of the heads and bodies at the ends of the rails being depressed downwardly from the plane of the upper face of the rail heads providing horizontal shelves, and upper ledges extending outwardly from opposite sides of the connector for resting on said shelves.
